UNITED STATES PATENT OFFICE.

WILLIAM E. WOODARD, OF FOREST HILLS, NEW YORK.

LOCOMOTIVE TRUCK AND BOILER DEVICE.

Application filed June 25, 1925. Serial No. 39,438.

This invention relates to locomotive truck and boiler devices and its nature, objects and advantages will be best understood from the following:

5 In the locomotive shown in my issued Patent, No. 1,536,036 of April 28th, 1925, and in that shown in my pending application Serial No. 39,437, filed June 25, 1925, the main frame, contrary to usual practice, 10 terminates in the region of the front end of the fire box and a supplemental frame is articulated to the main frame and extends rearwardly under the fire box end of the boiler, with capacity for lateral movement 15 with respect thereto. The front end and also the rear end of the fire box end of the boiler must be supported.

However, it is evident that in the absence of the main frame under the fire box, the 20 rear end of the boiler constitutes the sole means of transmitting weight from the super-imposed structure to the bearings over, or the support on, the articulated truck. From this, it follows that the connections 25 to the fire-box of the boiler, both at the rear end and at the front end, where it attaches to the main frame, must be very ample and capable of withstanding very high strains, due to the fact that engine travels over un- 30 even track and the resulting strains have to be transmitted thru these connections to the boiler structure, there being no main frame to help absorb the shocks.

The improvements consist, therefore, in 35 so forming the corners of the boiler fire box and of the mud-ring, which is fitted into the bottom of the fire-box, as to best withstand the shocks and carry the very heavy weights imposed.

40 How the foregoing, together with such other objects as may hereinafter appear, or are incident to my invention, are realized, is illustrated in preferred form in the accompanying drawings, in which—

45 Fig. 1 is a side elevation of the rear portion of the locomotive, such as hereinbefore mentioned, equipped with my improvements;

Fig. 2 is the bottom plan of half of the fire box; and

50 Fig. 3 is a fragmentary bottom plan of a portion of the fire box drawn to a large scale.

Referring now to the drawings, the reference numeral 7 indicates the barrel of the locomotive boiler and the reference numeral 55 8 indicates the rear or fire box end of the

boiler, such fire box having the usual front, rear and side water legs 9, the bottom of the water legs being formed by the mud-ring 10, which is secured to the sheets 11 forming the inside and outside fire boxes. The 60 main frame of the locomotive is indicated at 12 and, as above described, it terminates at the front end of the fire-box portion 8 of the boiler. The supplemental frame 13 is articulated to the main frame and extends under the fire box portion 8 of the boiler, the frame having any desired number of axles and wheels. The forward end of the fire box portion 8 of the boiler is carried on an expansion bearer 14 and the rear end thereof is carried on the supplemental frame by means of the bearer device 15, such, for example, as shown in the application of L. G. Tandy No. 639,730, now Patent 75 No. 1,555,330, granted Sept. 29, 1925, weight being transmitted to the bearer device thru the medium of the member 16, which is shown, described and claimed in my pending application Serial No. 26,012, filed April 27, 1925. This member, besides transmitting weight to the bearer, is a combined support for the cab, stoker and other rear end devices of the locomotive.

In carrying out my invention I form the 80 corners A of the fire box on a large radius, diminishing upwardly from the bottom and I also prefer that the inside and the outside radii be approximately the same so as to materially increase the space between the sheets at the corners. The corners of the 85 mud-ring are similarly formed. At the front the mud-ring has cast integral therewith three dependent lugs 17 for attachment to the expansion bearer device 14. At each corner at the rear, the mud-ring has dependent lugs 18 and 19, and intermediate the lugs 19 I provide a central lug 20, also cast integral with the mud-ring. The member 16, heretofore described, is bolted to the lugs 18 and 19.

100 It will be seen from the foregoing that the mud-ring is strong at the corners by virtue of the increased thickness of the mud-ring and that its strength is increased at the corners, particularly at the rear corners by the dependent lugs. Thus, in so far as the mud-ring itself is concerned it will be seen that it is constructed to withstand the high strains hereinbefore referred to. It will also be seen that the rounded corner construction 105 110

of the fire-box, and the boiler also, tends to produce the required strength.

The construction of mud-ring and fire box corners is very important in that I am enabled to use a plurality of thru bolts or rivets 21 to secure the sheets forming the water legs to the corner portions of the mud-ring. Heretofore it has only been possible to employ patch bolts of the character indicated 10 at 22 to secure the sheets to the corner portions of the mud ring. It will be obvious that such a frame or connection would be wholly inadequate and that leakage, if not much more serious difficulty, would develop 15 almost at once. However, by making the corners of sufficiently large radius and by having the mud-ring present a sufficiently large body of metal at the corners, thru bolts 21 may be safely employed and thus the 20 most rigid and stout connection between the boiler sheets and the mud-ring obtained.

It will be readily appreciated from the foregoing that the whole weight of the rear end may be transmitted thru the mud ring to 25 the bearing devices and on to the frames with safety.

What I claim is:

1. In a locomotive, the combination of fire box boiler sheets and mud-ring having the 30 corner portions thereof formed on radii such that thru bolts may be employed to connect

the sheets to the mud-ring at the corners, and thru bolts so securing the sheets.

2. In a locomotive, the combination of fire box boiler sheets and mud ring and thru 35 bolts connecting the straight flights and also the corners of the sheets to the mud-ring.

3. In a locomotive boiler having a fire box portion, a mud ring, the corners of which are formed on radii such as to increase the width 40 at the corners over the width of the straight flights of the mud-ring, said mud-ring having a pair of reinforcing lugs at corner portions thereof cast integral therewith.

4. In a locomotive structure, a boiler in 45 which the firebox end forms the principal means affording vertical stiffness to the locomotive structure at the rear end, a carrying truck under the firebox end transmitting buffing and pulling strains, and means 50 for reinforcing the corners of the firebox at the points where vertical loads are transmitted from that portion of the locomotive structure to the locomotive frame and the carrying truck, said reinforcing means including a mud ring widened at corners, through bolts securing the boiler sheets to the mud ring at such widened corners and depending lugs on the mud ring.

In testimony whereof, I have hereunto 55 signed my name.

WILLIAM E. WOODARD.
